UNITED STATES PATENT OFFICE.

REUBEN M. ROSE, OF NORWALK, CONNECTICUT.

SEAL.

SPECIFICATION forming part of Letters Patent No. 417,510, dated December 17, 1889.

Application filed December 29, 1888. Serial No. 294,972. (No model.)

To all whom it may concern:

Be it known that I, REUBEN M. ROSE, of Norwalk, county of Fairfield, and State of Connecticut, have invented new and useful 5 Improvements in Seals; and I do hereby declare that the following is a full and exact description of the same, reference being had to the accompanying drawings, and to the letters of reference marked thereon.

10 This invention is designed for use in a similar manner to other devices of this class; and it consists in certain peculiarities of construction, as will be fully described hereinafter.

15 In the drawings, Figure 1 represents a front view of the complete seal as it appears when in use. Fig. 2 is an edge view of one form of the seal. Fig. 3 is an edge view of another form of the seal. Fig. 4 is a view of the main portion of 20 one form of the seal. Fig. 5 is a similar view of another form. Fig. 6 is a sectional view of the form shown in Fig. 2 with one end of shackle E hooked on tongue D of disk portion A. Fig. 7 is a similar view with one end 25 of shackle E hooked in slot C, as shown in Fig. 4. Fig. 8 is a shackle having its ends turned over in a hooked shape. Fig. 9 is a similar view having portions of metal cut out to form a hook shape at either end, as G G.

30 To enable others skilled in the art to make my improved seal, I will proceed to describe fully the construction of the same.

Figs. 8 and 9 represent a shackle of any proper length and width, which is provided 35 at its end with a hook shape, as indicated by F F and G G.

Figs. 5 and 6 show the inside disk portion tongue D of disk A. Figs. 4 and 7 show a similar disk with slots C C.

40 Fig. 4 represents a disk B for one side of seal, with slots C C for the purpose of introducing into said slots the ends F F of shackle E, as shown in Fig. 7, when the disk H overlaps the periphery of disk B. By this means 45 the seal is made complete.

Fig. 5 represents another form of a disk A

for one side of seal, which is provided with an overhanging rim adapted to having one portion of said rim pressed down to form the tongue D, the remaining portion of said rim 50 to be closed down upon the periphery of a like disk A, with tongue portions D facing each other. After the disks are closed together by the overhanging rims the hook portions D form an opening to admit the introduction of the ends F F of shackle E, as shown in Fig. 6. By this means the seal is made complete.

The manner of using the seal is substantially as follows: The seal being in the condition indicated in Fig. 7, the slotted disk B being overlapped by disk H, and one end of shackle E passed into slot C, with its hooked, portion F between said disks B and H, the other end of shackle is passed through an 60 eye or staple or other parts which it is desired to secure or fasten. Then the portion F of said shackle is passed through the other slot C of disk B a distance sufficient to catch the portion F of shackle E over the inner 65 edge of slot C in disk B. By means of this construction a perfectly secure fastening is obtained.

Having thus fully described my invention, what I claim as new, and desire to secure by 70 Letters Patent, is—

1. In a seal, the combination of two or more disks adapted to be secured together and having one or more openings, and a shackle having hooked ends to engage in said openings, substantially as set forth.

2. In a seal, the combination of the disks H and B, adapted to be secured together, and one of said disks having slots C C, and the shackle E, having hooked ends F F, to engage 85 in said slots, substantially as set forth.

This specification signed and witnessed this 20th day of December, 1888.

REUBEN M. ROSE.
